CHARLES H. SHAW, OF BABYLON, NEW YORK, ASSIGNOR TO THE AEOLIAN COMPANY,
A CORPORATION OF CONNECTICUT.

SOUND BOX.

Application filed July 3, 1918. Serial No. 243,142.

To all whom it may concern:

Be it known that I, CHARLES H. SHAW, citizen of United States, residing at Babylon, Long Island, State of New York, have 5 invented new and useful Improvements in Sound Boxes, of which the following is a specification.

My present invention relates to a universal sound-box adapted to play with minimum adjustment both the lateral and hill-and-dale type of sound-records.

In the drawings in which I have shown only one of the specific embodiments my invention is adapted to take:—Fig. 1 is a 15 side-elevation of a sound-box within my invention shown on a tone-arm, the full lines showing it in playing position, the dotted in out-of-playing position; Fig. 2 is a sectional view of said sound-box, partly in elevation, on the line 2—2 in Fig. 1 looking in the direction of the arrows; Fig. 3 is an underneath plan view of the box as viewed from the arrows in Fig. 2; Fig. 4 is a cross-sectional view through the neck of the 25 sound-box and tone-arm on the line 4—4 in Fig. 2 looking in the direction of the arrows; Fig. 5 is a similar cross-sectional view through the neck of the sound-box and tone-arm except that it shows a slot 30 and set-screw form of connecting-means between the two parts; and Fig. 6 is an elevational view of said parts and modified form of connecting means shown in Fig. 5.

I will now describe the illustrated specific embodiment of my invention including the tone-arm:—1 is the elbow of the tone-arm swiveling about a vertical axis A—A and is to this end operatively supported in any well known manner in the stationary 40 flanged-sleeve-with-bracket member 2. 3 is the middle-section of the tone-arm which is pivotally supported on a pair of horizontal pivots or trunnions from the elbow 1, one of said pivots being indicated at 4 in Fig. 1. 5 is the free-end section of the tone-arm, one end of which has a rotary fit in the mouth of the tube 3, whereas its other end receives the neck of the sound-box. This end-section 5 is bent so as to bring the diaphragm and stylus in proper relationship to the record. In Fig. 1, the proper playing relationship of said parts to the record is shown by the full lines. When out of play, the sound-box and end-section 5 are twisted

into the dotted position shown in Fig. 1. 55 The end-section 5 is maintained rigidly in either of its said positions of rotation in the middle-section 3 by a spring-pressed pin 6 projecting through a hole in the section 3 and seating itself in holes or recesses in the 60 end-section 5 suitably positioned for the purpose; 7 is the leaf-spring whose free-end operatively supports this pin 6 and whose other end is secured at 8 to the section 3 of the tone-arm. The above mentioned 65 pivots 4 permit the sound-box and the tone-arm sections 5 and 3 to pivot up and down in following the record and any wobbling of the turn-table; whereas the swivelling axis A—A permits the sound-box and the 70 whole tone-arm to follow the sound-groove across the record.

The sound-box comprises any usual form of body 9, diaphragm 10, gaskets 11—11, and gasket retaining ring 12. 75

13 is a stylus-holder having a thumbscrew 14 for securing the stylus or needle 15 in any usual socket in the end of the holder. The stylus-holder with its needle is located in front of the diaphragm with 80 its longitudinal axis at right-angles thereto and in line with the center of the diaphragm. It is operatively supported in this position in a stationary ring 16 which is itself supported from the face of the sound-box on the legs of the spider 17. The stylus-holder 13 has trunnions 18—18 (best shown in Fig. 3) engaged by pivot-screws 19—19 which pivotally support said holder in the ring 16. 19 is a link pivoted at one end to 90 the upper end of the stylus-holder 13 and at the other end to one arm of an elbow-lever 20, whose other arm has a bent-foot which is secured to the center of the diaphragm. This elbow-lever is pivoted at 21 (Fig. 2) to 95 the rim of the sound-box. More specifically, 22 is a piece screwed to the periphery of the sound-box having a pair of spaced lugs 23—23 projecting beyond the face of the box. These lugs support the pivot-screws 100 21—21 whose points engage the enlarged sides of the elbow-lever 20 and thereby pivotally support said lever.

The result of this combination of devices is that vibrating the needle-point 15 from 105 right to left in Fig. 2 produces an in-and-out vibration of the diaphragm 10. This is the sort of vibration delivered by a lateral-cut

record to the stylus; and Fig. 1 shows the sound-box adjusted to play this type of record; the pivot 21 of the elbow-lever 20 in said figure, being at the edge of the sound-box-nearest the observer.

Now to adjust the sound-box to play hill-and-dale records, it is merely necessary to rotate it about its own axis through about 90° so that the pivotal axes 19 and 21 respectively of the stylus-holder 13 and elbow-lever 20 are now transverse to the longitudinal axis of the tone-arm instead of lengthwise. The result of this simple, rotary adjustment of the box is that up-and-down vibration delivered to the stylus in following a hill-and-dale record produces an in-and-out vibration of the diaphragm.

24 (Fig. 2) is a spring located between the face of the sound-box and the diaphragm-arm of the elbow-lever 20 to give the diaphragm preferably a slight normal tension in one direction.

The means for permitting this rotary adjustment is as follows:—25 (Figs. 2 and 4) is the usual flanged neck secured to the back of the sound-box concentric with the sound-opening through said back, except that instead of being fixed as usual in the mouth of the end-section of the tone-arm, 30 it is rotatable therein through 90° and back again. Means for releasably locking it in either of its adjusted positions is provided consisting of a spring-pressed pin 26 (Fig. 4) on the free end of the spring 27 projecting freely through a hole in the wall of the neck 25 into suitably placed recesses 27—27 on the inside wall of the tone-arm section 5, the leaf-spring 27 being attached at 28 to said neck 25.

40 Figs. 5 and 6 show merely a modification of this rotary adjustment and fastening means, wherein a T-shaped slot 29 is suitably provided in the tone-arm section 5 to cooperate with the stem of a thumb-screw 45 30 threaded into the neck 25. The stem-portion of the T-shaped slot permits the stem of the thumb-screw to pass in applying and removing the sound-box to and from the tone-arm, whereas the head-portion of slot 50 permits the desired extent of rotation of the box on the end of the tone-arm to adjust it to play one type of record or the other. Tightening the thumb-nut 30 locks the box in the desired adjustment.

55 This sound-box plays each type of record excellently.

Of course modifications are possible which will still be within the spirit of my invention.

60 What I claim is:

1. A sound box comprising a diaphragm, a laterally vibratable intermediately pivoted stylus holder operatively supported in front of the face of the diaphragm and having its inner end disposed adjacent and

transversely to the central portion of the diaphragm, and means for delivering the vibrations of the stylus holder to the diaphragm embodying an elbow-shaped stylus bar, the intermediate portion of which is 70 pivoted to the sound box and one arm of which is attached to the diaphragm, and a link operatively connecting the other arm of the stylus bar to the inner end of the stylus holder.

2. A sound box comprising a diaphragm, a laterally vibratable intermediately pivoted stylus holder operatively supported in front of the central portion of the face of the diaphragm and extending transversely thereto, an elbow-shaped stylus bar pivoted at the junction of its arms, the free end of one arm being attached to the diaphragm, and a link operatively connected to the inner end of the stylus holder and to the other arm of the stylus bar.

3. A sound box comprising a diaphragm, a spider arranged opposite to the diaphragm and having an apertured ring and radiating arms attached to the periphery of the sound box, a laterally vibratable stylus holder extending through and operatively supported by said ring of the spider in front of the central face portion of the diaphragm and extending transversely thereto, 90 and lever connections for delivering the vibrations of the stylus holder to the diaphragm.

4. A sound-box comprising a diaphragm, a stylus-holder located in front of the central face-portion of the diaphragm and having its inner and outer ends disposed transversely thereto, a support for said stylus-holder permitting it to pivot about an intermediate point of its length, an elbow-shaped stylus bar pivotally supported at an intermediate point on the periphery of the sound-box, one arm of said lever being operatively related to the diaphragm and the other arm extending from the box in a direction transversely of the diaphragm, the pivoting axes of the stylus-holder and of the stylus bar being substantially parallel, and a link extending in substantial parallelism with the plane of the diaphragm operatively connecting said transverse arm of the stylus bar with the end of the stylus-holder nearest the diaphragm.

5. A sound box comprising a diaphragm, a spider arranged opposite to the diaphragm 120 and comprising an apertured ring located in alinement with and opposite to the central portion of the diaphragm, and arms extending from the ring to the periphery of the sound box, a stylus holder extending longitudinally through the aperture in the ring of the spider, a transverse pivot supporting the stylus holder for vibration laterally within the aperture of the ring, a stylus bar operatively related to the diaphragm, 125 130

and an operative connection between the stylus bar and the inner end of the stylus holder.

6. A sound-box comprising a diaphragm, 5 a stylus-holder located in front of the central face-portion of the diaphragm and having both of its ends disposed transversely thereto, a support for said stylus-holder permitting it to pivot about an intermediate 10 point of its length, and an elbow-shaped stylus bar pivotally supported at a point intermediate its length on the periphery of

said box, one arm of the stylus bar being operatively related to the diaphragm and its other arm being operatively connected with 15 the inwardly extending end of the stylus-holder which is nearest the diaphragm, the pivoting axes of said stylus-holder and stylus bar being substantially parallel.

In testimony whereof, said CHARLES H. 20 SHAW, has signed his name to this specification, this second day of July, 1918.

CHAS. H. SHAW.
